UNITED STATES PATENT OFFICE.

THOMAS R. WAY, OF SPRINGFIELD, OHIO.

TAP-WRENCH.

SPECIFICATION forming part of Letters Patent No. 226,643, dated April 20, 1880.

Application filed January 29, 1880.

To all whom it may concern:

Be it known that I, THOS. R. WAY, a citizen of the United States, residing at Springfield, in the county of Clarke and State of Ohio, 5 have invented certain new and useful Improvements in Tap-Wrenches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention is in the nature of improvements in tap-wrenches, and is designed to afford a simple, cheap, and durable wrench, adapted to receive either an oblong or square headed tap, for general use by mechanics.

The invention relates more particularly to a stock having, if desired, changeable handles, and a slot constructed with one-half its head to receive flat or oblong-headed taps and the other half to receive square-headed taps, in combination with a follower similarly formed, 25 whereby the wrench is adapted for use with the variously-shaped taps usually found in the machinist's department.

In the drawings illustrating my invention, in the several figures of which like parts are 30 similarly designated, Figure 1 is a plan view of one side of the wrench, showing the form of slot-head and follower adapted for flat or oblong headed taps. Fig. 2 is a similar view of the opposite side, showing the form of slot-head and follower adapted for square-headed taps, with a portion of the follower broken away to illustrate the mode of connecting the follower with its adjusting-screws. Fig. 3 is a cross-section on line $x-x$ of Fig. 1, looking in 35 the direction of the arrow, and showing the follower in top view; and Fig. 4 is a perspective view of the parts of the follower separated.

A designates a tap-wrench stock, of metal, 45 and having handle-sockets a a' . The handles b b' may be of wood, and preferably are of equivalent material that will be easy on the hands. These handles may be screw-threaded and inserted in correspondingly-threaded recesses in the sockets a a' , or the 50 parts a b and a' b' may be in one piece with

the stock A. The handle or socket a is screw-threaded at c , and works in a correspondingly-threaded orifice in the part d of the stock, and the inner end of the threaded portion c is made 55 with a button or disk, e , upon which a follower, B, is secured.

The stock A is slotted at C, into which slot the screw e extends, and one half or part of the head f of such slot is made with two faces, 60 g g , extending upon parallel lines and connected by a right-angled face, as shown in Fig. 1 of the accompanying drawings, and the opposite half or part with a straight face, h , preferably provided with a right-angled notch, 65 as shown in Fig. 2.

The follower B is made in two parts, 1 2, one of such parts, 1, having a face, i , matching the faces g g of the slot-head f , and the other part, 2, having a face, j , matching the 70 straight face h of said slot-head, and, like it, having a right-angled notch. This follower has flanges k , adapted to slide upon the edges or walls l of the slotted stock. The meeting or inner faces of the two parts 1 2 of the follower are recessed, as at m n , to permit of their inclosing the button or disk e of the screw e , and when so placed about such screw, within the slot C, the said parts are united by a screw-bolt or rivet, o , whereby the follower 80 is secured to and may be adjusted in the slot by the movable screw-threaded handle.

It will be understood that the button e turns easily within the cavity formed in the follower by the recesses m n in the halves 1 2 of such 85 follower, so as to admit of the easy and ready adjustment of the follower without binding in the slot. The flanges k of the follower, sliding on the walls l of the slot, serve to guide and steady the follower in its movement and confine it within the slot.

It will be readily understood that in using this tap-wrench the tap or die is placed, according to its oblong or square shape, on the corresponding face of the slot-head, and the 95 follower moved up to it by means of its screw-carrier until such tap or die is immovably held between the slot-head and follower, when the wrench is ready for use.

Having described my invention, what I claim is—

1. A stock having a slot whose head is con-

structed with differently-shaped faces, in combination with a follower provided with correspondingly-shaped faces, and with an operating screw-handle, substantially as shown and described.

5 2. In a tap-wrench, a slotted stock, in combination with a screw-handle having a button, *e*, and a flanged recessed follower, *B*, con-

structed in two parts, and a screw-bolt, *o*, substantially as shown and described.

In testimony whereof I affix my signature to in presence of two witnesses.

THOMAS R. WAY.
